ART OF CRACKING HYDROCARBON OILS

Filed April 9, 1927

UNITED STATES PATENT OFFICE

EDWARD W. ISOM, OF SCARSDALE, NEW YORK, ASSIGNOR TO SINCLAIR REFINING COMPANY, OF NEW YORK, N. Y., A CORPORATION OF MAINE

ART OF CRACKING HYDROCARBON OILS

Application filed April 9, 1927. Serial No. 182,355.

This invention relates to improvements in the cracking of heavier hydrocarbon oils, such as gas oil or kerosene to produce therefrom lighter hydrocarbon oils, such as gasoline line or gasoline-containing distillates.

Lighter hydrocarbon oils are usually more refractory with respect to elevated temperatures than are heavier oils. Gas oil, for example, will crack more rapidly at a lower temperature than will a lighter kerosene. If subjected to higher temperatures, however, heavier oils tend to be overcracked with accompanying losses.

This invention relates particularly to improvements in a combined cracking operation in which various oils of different characters are subjected to cracking conditions advantageous with respect to the individual oils.

This application is in part a continuation of my prior application filed August 28th, 1922, Serial Number 584,711.

The present invention will be more particularly described in connection with the accompanying drawing which illustrates, in a diagrammatic and conventional manner, in elevation and partly in section, one form of apparatus adapted for the practice of the process of my invention.

In the drawing, a single pass heating conduit 1 is shown discharging into a shell or reservoir or enlarged chamber 2 from which vapors are discharged through connection 3 successively through reflux towers 4 and 5. Vapors from the reflux tower 5 pass through connection 6 to a condenser (not shown). The condenser is of ordinary construction and is connected to a receiver in the usual way. The reflux tower 4 is provided interiorly with baffles, oil for refluxing the vapors being introduced into direct contact with the vapors through connection 7. Reflux tower 5 is provided interiorly with tubes through which the vapors pass, the refluxing medium being circulated about the tubes in indirect heat exchanging relation with the vapors passing through the tubes.

In referring to single pass operation, reference is intended to operation in which the oil supplied to the heating conduit is circulated but once therethrough. I intend to

include operations in which vaporized fractions may be refluxed and recirculated from the oil heating conduit, but to exclude operations in which unvaporized portions of the oil supplied are recirculated through the heating conduit.

The heating conduit 1 is arranged in a heating furnace 8. This furnace, as illustrated, is advantageously provided with means for recirculating over the heating conduit in admixture with fresh hot products of combustion a portion of the heating gases which have previously passed thereover. The enlarged chamber 2 is also shown arranged in a heating furnace 9. The enlarged chamber 2 may, with advantage, be heated internally only by the heat supplied by the hot products discharged from the heating conduit 1, but this heating may be supplemented by additional heating by means of the furnace 9.

In carrying out the present invention in the apparatus illustrated, oil is forced in a single pass through the heating conduit 1 by means of the pump 10. In this heating conduit the oil is heated to a cracking temperature, for example, to a temperature of about 800° F. to 1200° F., as it is discharged from the heating conduit. In the enlarged chamber 2, the vapors of the cracked oil separate from any unvaporized portions. These vapors then pass successively through the reflux towers 4 and 5 in each of which heavier portions of the vapors are condensed. In the first refluxing operation, that carried out in tower 4, fresh oil, supplied by means of pump 11, is introduced into direct contact with the vapors. The fresh oil is thus heated and the vapors thus cooled and condensed. Likewise, any intermediate constituents which the fresh oil may contain are vaporized and escape from the refluxing operation together with the vapors from the cracking operation remaining uncondensed. The fresh oil so supplied to the first refluxing operation is advantageously of a heavier character, although it may contain intermediate constituents. The present invention is of special value and application, in connection with the treatment of such relatively heavy oil containing in-

termediate constituents. The vapors from this first refluxing operation are then subjected to a second refluxing operation, that effected in tower 5. Here the vapors are cooled and condensed by indirect heat exchange with oil supplied through connection 12, this fresh oil at the same time being heated.

Fresh oil, particularly fresh, heavier oil, 10 may be supplied directly to the reflux tower 4, by means of pump 11, through connections 13 and 7, and the cooling requisite to the second refluxing operation effected by some external means. It is advantageous, however, 15 to employ this fresh oil, previous to introduction into reflux tower 4, for effecting the cooling requisite to the refluxing operation carried out in tower 5. The fresh oil, particularly fresh, heavier oil, may thus be 20 passed in indirect heat exchanging relation with the vapors in reflux tower 5, by means of connection 12 and then conveyed to reflux tower 4 by means of connections 14, 15 and 7. In the latter procedure, the refluxing in 25 tower 5 may be regulated by bypassing a part of the fresh oil through connection 13. Likewise, the refluxing in tower 4 may be regulated by bypassing part of the fresh oil supplied through either or both connections 30 13 and 14 through connection 16. Fresh oil bypassed through connection 16 may be discharged into the chamber 2 through connections 17 and 18 or returned to storage through connection 19.

35 The relatively heavier reflux condensate, and admixed, unvaporized, fresh oil, from reflux tower 4 is advantageously returned to the enlarged chamber 2 through connections 20, 21 and 18. Part of this mixture, however, 40 may be supplied to the receptacle 22 through connections 23 and 24. The relatively lighter condensate from the reflux tower 5 is conveyed to the receptacle 22 through connections 25 and 24. The receptacle 22, as well as the connections for returning hot condensates from the reflux towers thereto, is advantageously insulated against heat loss. In carrying out the invention the reflux condensate collecting in this 45 receptacle may thus be returned to the operation at temperatures as high as 500° F. or even somewhat higher. In the second refluxing operation, that carried out in tower 5, intermediate constituents vaporized from the fresh oil introduced into tower 4 are condensed and flow to the receptacle 22 with the reflux condensate.

50 The oil collecting in receptacle 22 is forced into the heating conduit 1 by means of the pump 10. Additional fresh oil, particularly fresh, lighter oil, may also be supplied to this receptacle 22 through connection 26. Fresh oil supplied through connection 26 mingles with the hot reflux condensate in receptacle 55 22, being thereby preheated, and is supplied

to the heating conduit 1 in admixture therewith.

The operation carried out in the enlarged chamber 2 may be one of several. A body of oil may be maintained therein and subjected to cracking either by the heat supplied internally by the hot products discharged from the heating conduit 1 or by this heat supplemented by additional heat supplied by the furnace 9. This is a particularly advantageous operation for cracking heavier oils or oils which crack with an excessive formation of carbon and pitch. In such operation, oil may be discharged from this body, either continuously or intermittently, through connection 27. In addition to the fresh oil supplied to this chamber 2 through connection 16 and, in admixture with the relatively heavy condensate, through connection 21, additional fresh oil, particularly very heavy oil or easily cracked oil, may be supplied thereto through connections 19, 17 and 18. Or, the operation carried out in chamber 2 may be such as to reduce to coke the oil residues collecting therein. In such operation, it is advantageous to do away with external heating of this chamber. In such operation, the discharge of oil through connection 27 may be omitted, or oil may be discharged through this connection during an initial period of operation and this discharge stopped and the operation carried out for the production of coke in a subsequent period of operation.

55 In the operation of the invention, lighter and more refractory oils are subjected to advantageous cracking conditions in the heating conduit 1 and heavier and less refractory oils are subjected to advantageous cracking conditions in the enlarged chamber 2. By 60 maintaining less severe cracking conditions in the enlarged chamber 2, overcracking of such heavier and less refractory oils is avoided while the operation of enlarged chamber 2 is adapted to accommodate cracking of such oils as results in formation of fairly 65 large amounts of carbon and pitch. To illustrate, in the operation of the present invention, the charging stock supplied to the tower 4 through connection 7 may be an average 70 gas oil. Lighter charging stock, such as a light gas oil or kerosene, is advantageously supplied to the receptacle 22 through connection 26. Very heavy oils to be cracked, such as heavy gas oils, fuel oils or residues, or 75 oils which tend to form large amounts of carbon or pitch when subjected to cracking, may be supplied directly to the enlarged chamber 2 through connection 19. The operation of the invention is particularly 80 advantageous in the treatment of oils containing intermediate as well as heavier constituents. Such oils are supplied to the reflux tower 4 through connection 7, the intermediate constituents being vaporized by the heat 85

exchange with the vapors in this tower and being again condensed in tower 5. The vaporization of these constituents assists in refluxing heavier portions of the vapors in the tower 4. At the same time, a separation of the charging stock is made so that the heavier and intermediate constituents are individually subjected to advantageous cracking conditions, the heavier constituents, at least in part, being supplied to the enlarged chamber 2 and the intermediate constituents being supplied to the receptacle 22 from which, in admixture with lighter reflux condensate and any lighter fresh oil, they are forced through the heating conduit 1.

The enlarged chamber 2 is advantageously maintained under elevated pressure to repress vaporization of constituents undergoing cracking for the production of components desired in the product under the conditions prevailing therein. For the production of gasoline or gasoline-containing pressure distillates, for example, the pressure in the enlarged chamber may, for example, be maintained in the neighborhood of 50 to 150 pounds per square inch. The oil supplied to the heating conduit 1 may be forced into this heating conduit under pressure just sufficient to drive it therethrough and discharge the resulting products into the enlarged chamber 2, or the heating conduit 1 may be maintained under a higher pressure than that prevailing in the enlarged chamber 2 and the pressure reduced between the heating conduit and the enlarged chamber. The reflux tower 4 is advantageously operated under substantially the same pressure as that prevailing in the enlarged chamber 2, to avoid the necessity of using a pump for returning admixed reflux condensate and unvaporized fresh oil from this reflux tower to the enlarged chamber. Where a part of the admixed reflux condensate and unvaporized fresh oil from reflux tower 4 is supplied to the receptacle 22, it is also advantageous to operate the reflux tower 5 under substantially the same pressure. The reflux tower 5 may, however, be operated under a lower intermediate pressure or at substantially atmospheric pressure and the pressure reduced between the two reflux towers, or the pressure may be maintained on the system through both reflux towers and reduced between the second reflux tower and the condenser, or the pressure on the system may be maintained through the final condenser. In place of supplying fresh oil to receptacle 22, fresh oil to be forced through the heating conduit 1 may be supplied directly to the suction of the pump operating for this purpose, or a separate pump may be used for forcing such fresh oil through the heating conduit.

I claim:

1. An improved method of cracking hydrocarbon oils, which comprises forcing oil in a single pass through a heating conduit

and heating it to a cracking temperature therein, discharging the hot oil from the heating conduit into an enlarged chamber, taking off vapors of the cracked oil from the enlarged chamber and subjecting these vapors successively to a first and second refluxing operation, passing fresh oil first in indirect heat exchanging relation with the vapors in the second refluxing operation and then introducing the thus heated fresh oil into direct contact with the vapors in the first refluxing operation, supplying admixed reflux condensate and unvaporized fresh oil from the first refluxing operation to the enlarged chamber, and supplying reflux condensate from the second refluxing operation to the heating conduit.

2. An improved method of cracking hydrocarbon oils, which comprises forcing oil in a single pass through a heating conduit and heating it to a cracking temperature therein, discharging the hot oil from the heating conduit into an enlarged chamber, taking off vapors of the cracked oil from the enlarged chamber and subjecting these vapors successively to a first and second refluxing operation, passing fresh oil first in indirect heat exchanging relation with the vapors in the second refluxing operation and then introducing the thus heated fresh oil into direct contact with the vapors in the first refluxing operation, supplying admixed reflux condensate and unvaporized fresh oil from the first refluxing operation to the enlarged chamber, supplying reflux condensate from the second refluxing operation to the heating conduit and supplying additional fresh oil to the heating conduit.

3. An improved method of cracking hydrocarbon oils, which comprises forcing oil in a single pass through a heating conduit and heating it to a cracking temperature therein, discharging the hot oil from the heating conduit into an enlarged chamber, taking off vapors of the cracked oil from the enlarged chamber and subjecting these vapors successively to a first and second refluxing operation, passing fresh oil containing heavy and intermediate constituents first in indirect heat exchanging relation with the vapors in the second refluxing operation and then introducing the thus heated fresh oil into direct contact with the vapors in the first refluxing operation, vaporizing intermediate constituents from the fresh oil in the first refluxing operation and condensing heavier vapors therein, condensing in the second refluxing operation intermediate constituents vaporized from the fresh oil in the first refluxing operation, supplying admixed reflux condensate and unvaporized fresh oil from the first refluxing operation to the enlarged chamber, and supplying reflux condensate and condensed intermediate fresh oil con-

stituents from the second refluxing operation to the heating conduit.

4. An improved method of cracking hydrocarbon oils, which comprises forcing oil 5 in a single pass through a heating conduit and heating it to a cracking temperature therein, discharging the hot oil from the heating conduit into an enlarged chamber, taking off vapors of the cracked oil from 10 the enlarged chamber and subjecting these vapors successively to a first and second refluxing operation, introducing fresh oil containing heavy and intermediate constituents 15 into direct contact with the vapors in the first refluxing operation, vaporizing intermediate constituents from the fresh oil in the first refluxing operation and condensing heavier vapors therein, condensing in the second refluxing operation intermediate constituents 20 vaporized from the fresh oil in the first refluxing operation, supplying admixed reflux condensate and unvaporized fresh oil from the first refluxing operation to the enlarged chamber, and supplying reflux condensate 25 and condensed intermediate fresh oil constituents from the second refluxing operation to the heating conduit.

5. A process of cracking hydrocarbon oil, consisting in passing oil through a coil 30 disposed within a heating zone wherein the oil is raised to a conversion temperature, in discharging the highly heated oil from said coil into an enlarged reaction chamber wherein conversion occurs, in passing the evolved 35 vapors through a primary dephlegmator wherein only the less refractory constituents of the vapors are condensed, in introducing in the said primary dephlegmator a second oil differing in characteristics from the oil 40 passing through the coil to act as a dephlegmating medium for the vapors therein, in passing the reflux condensate collected in said primary dephlegmator together with the unvaporized portions of the second oil introduced thereto into said reaction chamber, and in further dephlegmating and condensing 45 the vapors issuing from said primary dephlegmator.

In witness whereof, I have subscribed my
50 name.

EDWARD W. ISOM.
